RADIANT HEATER

Edwin J. Cowan, 275 Manzanita,
Sierra Madre, Calif. 91024

Filed Mar. 5, 1971, Ser. No. 121,611

Term of patent 7 years

Int. Cl. D23—03

U.S. Cl. D23—122

FIG. 1 is a perspective view of a radiant heater showing my new design;

FIG. 2 is a front elevational view of the radiant heater on an enlarged scale;

FIG. 3 is a right side elevational view thereof;

FIG. 4 is a left side elevational view thereof;

FIG. 5 is a rear elevational view thereof; and

FIG. 6 is a bottom plan view thereof.

The mesh is partially shown on the front of the heater in FIGS. 1 and 2 for convenience of illustration.

I claim:

The ornamental design for a radiant heater, substantially as shown and described.
